US0D1096803S

(12) **United States Design Patent** (10) Patent No.: **US D1,096,803 S**
Clarke et al. (45) Date of Patent: ** Oct. 7, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Graham R. Clarke**, Scotts Valley, CA (US); **Chia Yang Lin**, San Francisco, CA (US); **William A. Sorrentino, III**, Mill Valley, CA (US); **Andre Souza Dos Santos**, San Jose, CA (US)

(73) Assignee: **Apple Inc.**, Cupertino, CA (US)

(**) Term: **15 Years**

(21) Appl. No.: **29/946,514**

(22) Filed: **Jun. 9, 2024**

(51) LOC (15) Cl. **14-04**

(52) U.S. Cl. **D14/485**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost broken lines in the figures show a display screen or portion thereof, and form no part of the claimed design. The other broken lines in the figures show portions of the graphical user interface that form no part of the claimed design.

1 Claim, 1 Drawing Sheet
